TRAVELING LAWN SPRINKLER

William D. Egly, South Bend, and Columbus W.
Harris, Elkhart, Ind.

Application November 4, 1946, Serial No. 707,554

10 Claims. (Cl. 299—50)

1

This invention relates to improvements in traveling lawn sprinklers, and particularly to that type of lawn sprinkler which is adapted to traverse a path determined and controlled by the position of the flexible water conduit or hose which connects the sprinkler to a source of water under pressure.

The primary object of the invention is to provide a novel and simple device of this construction, which is effective for its intended purpose and which is sturdy and substantially trouble free in operation.

A further object is to provide a sprinkler of this type in which the operating parts are effectively lubricated at all times.

A further object is to provide a device of this character wherein the working parts are lubricated, which is so constructed that leakage of water into the lubricated portion thereof is entirely avoided.

A further object is to provide a device of this character with valve means for stopping the operation of the sprinkler when it reaches a predetermined position, which valve means are so constructed that leakage of water incident to the operation of closing the valve means is entirely avoided.

A further object is to provide a device of this character with means for releasing pressure trapped within the same and the conduit leading thereto after the valve means of the sprinkler has been closed and the water supply to the sprinkler has been cut off at the water tap.

A further object is to provide a device of this character having a novel and simple construction of driving means connecting a water pressure responsive operating member with the wheels supporting the sprinkler.

A further object of the invention is to provide a device of this character having a drive transmitting means for operating the wheels of the device in the nature of a pawl and ratchet mechanism which is so constructed that disengagement of the parts is prevented while at the same time permitting free lateral play of the parts within predetermined limits.

Other objects will be apparent from the following specification.

In the drawing:

Fig. 1 is a side view of the device with parts shown in section taken on line 1—1 of Fig. 2.

Fig. 2 is a top plan view of the device.

Fig. 3 is a view of the device in side elevation.

Fig. 4 is a rear end view of the device.

2

Fig. 5 is a detail sectional view of the device taken on line 5—5 of Fig. 4.

Fig. 6 is a fragmentary detail sectional view of the device taken on line 6—6 of Fig. 5.

Fig. 7 is a detail transverse sectional view of the device taken on line 7—7 of Fig. 5.

Fig. 8 is a top plan view of the valve control mechanism of the device.

Fig. 9 is a detail view showing the front end of the housing of the device.

Referring to the drawings which illustrate the preferred embodiment of the invention, the numeral 10 designates a housing or frame of the device which includes an upper casing part 11 and a lower casing part 12. These parts are held in fixed relation as a unit by side plates 13 of which one thereof, as best illustrated in Fig. 3, may be removable for access purposes.

The upper casing part 11 has a top wall 14 and a bottom wall 15 in which are formed axially aligned apertures to receive and journal an elongated rigid tube or conduit 16. The opening in the upper wall 14 is preferably of smaller diameter than the opening in the lower wall 15, and a shoulder 17 is formed on the conduit 16 to bear against the inner surface of the top wall 14 to prevent vertical displacement of the conduit 16 within the casing. The conduit 16 also has integrally or otherwise formed thereon screw-threaded teeth 18 in the portion thereof confined within the housing 11. Any suitable bearings (not shown) may be provided to journal the end portions of the conduit 16 within the housing walls. A shaft 19 is journaled in the housing 11 in laterally spaced relation to and perpendicular to the conduit 16 and a gear 20 is fixedly mounted upon the shaft 19 in meshing relation to the screw-threaded teeth 18 on the conduit 16. Consequently, it will be observed that rotation of the vertical tube 16 serves to rotate the shaft 19 at a substantially reduced speed.

The lower casing part 12 is spaced below the casing part 11 to provide a channel or passageway 21 between said parts, which passageway is open at its ends and preferably is characterized by a flaring mouth portion defined in part by a downwardly curved upper surface 22 on the part 12. The casing part 12 has a bore axially aligned with the tube 16 and mounting a bearing sleeve 23 in which the lower end portion of the conduit 16 fits and is journaled. A valve chamber 24 is formed in the casing 12 in axially aligned relation to and below the lower end of the tube 16 and the bearing 23. A lateral passage 25 opens into the valve chamber 24 and termi-

nates in an outer screw-threaded bore portion in which a rigid conduit 26 is screw-threaded to project rearwardly therefrom. The conduit 26 mounts an internally screw-threaded socket 27 at its outer end. The socket 27 is adapted to receive a screw-threaded coupling or fitting 28 mounted upon the free end of an elongated flexible water hose or tube 29 of the type well known in the art and which is adapted to be connected to a water tap or other source of water under pressure (not shown).

A depending valve control chamber 30 is secured to the bottom of the casing 12 and has a vertical guide passage therein axially aligned with the tube 16 and the valve chamber 24 for receiving cylindrical valve element 31 adapted to slide vertically therein. The valve element 31 has a flaring upper marginal portion adapted in normal position, as illustrated in full lines in Fig. 1, to seat upon a tapered socket 32 formed in the bottom of the casing 12 and defining the lower portion of the valve chamber 24. Valve element 31 is also provided intermediate its ends with a circumferential groove 33 in which a ball 34, slideable in a transverse bore in the valve casing 30 and normally urged toward the valve plug by a spring 35, is adapted to seat. The construction of these parts is of such a character that the spring pressed ball 34, which seats in the groove 33 of the valve element, normally serves to hold said valve element closed to permit free flow of fluid from the conduit 29 through the tube 26 into the valve chamber 24 and the conduit 16.

The valve guiding passage in the element 30 forms a part of a passage or opening of substantial U-shape and including pressure relieving by-pass 36 with which a by-pass 37 in the casing 12 communicates, said by-pass 37 opening into the passage 25 in the casing part 12. As illustrated, the by-pass 37 is preferably a small sectional area compared to the cross-sectional area of the passage 25. A transverse shaft 38 is journaled in the valve part 30 with its inner end extending into the passage 36. The inner end of the shaft 38 has a downwardly offset portion 39, and from the lower end of this offset 39 projects a finger 40 which projects under the valve element 31, as illustrated in Fig. 1. An upwardly projecting link 41 is secured to the outer end of the shaft 38 and is pivotally connected at its free end to an elongated horizontal longitudinally extending actuating member 42, for purposes to be hereinafter set forth.

The T-fitting 45 is threaded upon the upper end of the conduit 16 and tubular sprinkler arms 46 are secured to the arms of said fitting in horizontal radial relation. Where two tubular arms 46 are provided, the same are preferably arranged in axial alignment as illustrated. The outer ends of the sprinkler arms 46 are curved laterally upwardly and mount sprinkler heads 48 provided with apertures 49 for discharging water therefrom. The fitting 45 has a central aperture 50 therein adapted to slidably receive an elongated vertical rod 51 mounting a head 52 at its outer end and adapted to bear at its inner end upon the top of the valve plug 31. A stop 53 is formed upon the rod 51 at the portion thereof within the conduit 16 spaced below the top wall 50 of the fitting a distance less than the height of the valve chamber 24.

A pair of elongated longitudinally extending bracket arms 60 are secured at opposite sides of the side plates 13 of the frame member 10 and project therefrom at their opposite ends. The

rear end portion 61 of these arms 60 journals a transverse shaft 62 which mounts ground engaging wheels 63, here illustrated as provided with transversely ribbed peripheral rim portions 64. The forward ends of the bracket arms 60 converge and are rigidly interconnected by a member 65 in which is journaled a vertical shaft 66 projecting from a clevis 67 which rotatably mounts a wheel 68 at its lower end. The wheel 68 has an axial peripheral contour substantially conforming to the cross-sectional shape of the flexible water hose 29 to be guided thereby when riding upon the same. The elongated rod 42 extends alongside one of the bracket members 60 and is positioned by and slidably endwise in a guide 69 carried by said bracket arm 60. The forward end of the elongated rod 42 terminates in a head 70 positioned adjacent to and preferably forwardly spaced from the wheel 68.

The shaft 62 mounts a ratchet wheel 71 fixedly thereon intermediate its ends and laterally spaced from the adjacent bearing 64 journaling the same with reference to bracket arm 60. The ratchet wheel is provided with rigid teeth 72 of hooked or curved shape whereby a member pressing thereagainst in one direction serves to rotate the ratchet wheel, while pressure thereon in the opposite direction results in sliding of the member over the teeth. The shaft 19 mounts an arm or link 73 at its outer end projecting from the casing part and secured thereto as by a set screw 74 to rotate with said shaft. A stud shaft 75 is carried by the outer end of the arm 73 and spaced in parallel relation to the shaft 19. A pair of elongated rigid arms 76 preferably formed of sheet metal in channel shape, as best illustrated in Fig. 7, are pivoted at one end 77 to the shaft 75. The elongated arms 76 fixedly mount cross-pins 78 at their opposite ends, said arms being of such a length that the pins 78 are adapted to engage teeth 72 of the ratchet disk 71. The channel shaped arms are positioned oppositely to fit around substantially diametrically opposed parts of the disk 71, as illustrated in Fig. 6. The central portion of each of these arms is preferably cut away at 79 from a point adjacent the cross-pins 78 for a substantial extent, as illustrated in Fig. 6, whereby the teeth 72 of the disk intervening between the tooth engaged by the pin 78 and the pivot mounting of said arms 76 may fit freely in said cutaway to avoid interference with radial play of the arms with reference to the disk. A spring member 80 of substantially V-shape, whose central portion constitutes a coil 81 encircling the shaft 75 and whose outer ends are bent to provide hooks 82 engaging the outer edges of the arms 76, serves to urge said arms 76 inwardly and against the disk 71.

In the use of the device, assuming that the sprinkler has been connected to the flexible water conduit 29 at the socket 27, the device is first positioned with its guide wheel 68 straddling or riding upon the hose or conduit 29. The hose or conduit will be positioned upon the ground to extend along a line which constitutes the longitudinal center of the area which is to be sprinkled. A stop, such as a brick or other fixed abutment (not shown), is positioned adjacent the end of the conduit 29 opposite that to which the sprinkler is connected at a position which marks the opposite end of the area to be sprinkled. In other words, the sprinkler is positioned at one end of an elongated area to be sprinkled, and the abutment is positioned along-

side or adjacent the hose at the other end of the area to be sprinkled. When a supply of water is passed through the conduit 29 as by opening the water supply tap or valve, water flows through the conduit 29, the pipe 26, into and through the valve chamber 24, and thence through the conduit 16 and the sprinkler arms 46 for discharge from the sprinkler heads 48. By virtue of the rotatable mounting of the conduit 16 and the water reactance shaping of the ends of the sprinkler arms 46, the arms 46 are caused to rotate incident to the flow of water therethrough under pressure, thereby rotating the conduit 16. As the conduit 16 rotates, it transmits a driving force through the screw teeth 18 to the gear 23 and thereby drives the shaft 19 at a reduced speed. The rotation of the shaft 19 is transmitted to the arm 73 and thereby causes the arms 76 to be moved longitudinally.

Assuming that the shaft 19 operates in a clockwise direction as viewed in Fig. 6, it will be apparent that movement of the shaft 19 to swing the arms 73 from the position shown will cause both of the arms 76 to move bodily toward the right in the first quarter revolution of the shaft 19. Such movement causes the pin 78 on the uppermost arm 76 to act upon the adjacent tooth 72 to rotate the ratchet disk 71 in a clockwise direction. During this time the lower arm 76, moving in the same direction, has its pin 78 riding over the convex face of the adjacent tooth 72 in a counterclockwise direction, which causes the pin 78 to move to the next seat or space between the teeth 72 in a counterclockwise direction. Subsequent rotation of the shaft 19 causes endwise movement of the arms 76 downwardly and to the left, as viewed in Fig. 6. When that movement occurs, the pin 78 on the right-hand lower arm 76 will press in a clockwise direction against the adjacent ratchet tooth 72 to continue the clockwise rotation of the disk 71, while the upper or left-hand arm 76 in its movement in the same direction traverses freely over the convex face of the adjacent ratchet tooth 72 to seat behind that tooth in preparation for the reverse movement of the parts in which it will again serve to impart a driving impulse to the ratchet disk. In other words, the arms 76 alternately drive the disk in the same rotational direction and, during the period between working operations thereof, have a lost motion connection with the disk to take a new position with reference to the disk. It will be observed that the spring 81 holds the arms in firm operative relation to the disk, and that the arrangement of the flanges of the U-shaped arms on opposite sides of the disk insures against lateral release or disengagement of the arms with the disk incident to the operation of the device, which, as aforementioned, is characterized by movement of the pins 78 radially relative to disk 71 as the same slide over the teeth of the disk to take a new working position.

When the sprinkler propelled as described above has traversed the area to be sprinkled, it reaches a position at which the head 70 on the rod 42 abuts the stop hereinabove mentioned, so that continued propulsion of the sprinkler serves to slide the rod 42 rearwardly, as viewed in Figs. 2 and 3. This rearward movement of the rod 42 serves to pivot the link 41 and thereby rotate the shaft 38 in a manner to swing the free end of the finger 40 in an upward direction. As the finger 40 swings upwardly it engages the valve member 31 and presses the same upwardly to release the engagement of the spring pressed ball 75

34 from the peripheral groove 33 in the valve element. Continued pivotal or swing movement of the finger 40 bodily elevates the valve element until the upper surface thereof seats against the lower end of the bearing 23 to thereby close or seal the discharge opening of the valve casing 12 so that the flow of water to the tube or conduit 16 is shut off. The valve element 31 is of such length that it is guided through its full stroke by the guide passage therefor within the depending chambered valve member 30. It will be observed that this upward movement of the valve simultaneously shifts the rod 51 upwardly to the dotted line position shown in Fig. 1. The valve member 31 closes the valve chamber 24, and the continuance of water pressure from the tap is diverted through the by-pass 37 and the passage 36 in the member 30 to act upon the bottom of the valve member 31 and thereby hold the valve member in its seated position.

It will be observed that by virtue of this arrangement of the parts, the valve is effectively closed and the device is sealed against the leakage of water therefrom without requiring attention of the user. Subsequently, when the user attends to the sprinkler, he may move it to a new position without closing the water tap to shut off line pressure if he exerts care to hold the rod 42 in its valve closing position and to avoid pressing the rod 51. The only danger to the user in such an operation occurs when he releases the member 42 and depresses the rod 51 to permit resumption of the sprinkling operation and during the time required for him to move out of the range of the sprinkler. In view of the latter condition, the customary procedure of the user after a given area has been sprinkled will be to first turn off the line pressure at the water tap. It will be observed, however, that when this is done there still remains a quantity of water in the hose or conduit 29 which is at line pressure. The user can easily release this line pressure preparatory to moving the hose by pressing against the head 52 of the rod 51 to unseat the valve member 31. Inasmuch as the pressure trapped within the hose 29 is quickly dissipated, no danger of being wetted is experienced by the user if he takes care to so adjust the sprinkling arms that the short pressure releasing spurt of water resulting when the rod 51 is depressed is not directed toward himself. Having depressed the rod 51, the sprinkler may be moved to any desired new position without danger of water leaking from the device, and the device can be again set into play by simply turning on the water tap at the intake end of the conduit 29.

Another advantage of the device which is of primary importance is the arrangement of the parts to provide the passage 21 between the gear casing 11 and the casing part 12. In order to insure free running of the parts, it is contemplated that the gear casing will contain a grease or other lubricant. As long as this lubricant remains unaffected by leakage of water into the gear casing, the free operation of the device is assured. This assurance is obtained by the spacing of the gear casing 11 from the casing part 12 and the interposition of the passage 21 which is partly defined by the downwardly curved surface 22. It will be apparent from consideration of the arrangement of the parts, as illustrated in Fig. 1, that if there is any tendency for water to leak from the casing 12 by virtue of the rotating fit of the conduit 16 within the bearing 23 and by virtue of the water pressure, that leakage extends

into the passage 21 where its pressure is dissipated so that it drains through the passage. Since pressure of the leakage is dissipated it is prevented from entering into the casing 11 as would otherwise occur if the discharge passage 21 was not provided. Therefore, it will be apparent that the construction and arrangement of the parts as shown prevents the occurrence of leakage into the lubricated gear casing 11 so that rusting of the working parts or other conditions tending to prevent free operation of the parts is avoided.

Other advantages of the device which will readily be apparent are the accessibility of the parts, their ease of assembly and the avoidance of all constructions which would tend to require repair or replacement of parts. Thus it will be apparent that full access to the gear casing 11 may be had by simply removing one of the removable side plates 13. Full access to the valve chamber is had by removing the chambered member 30 from the bottom of the housing unit. Likewise for ease of assembly the same relation of the parts permits sub-assemblies to be easily effected for assembly in turn with other sub-assemblies to produce a complete device. The drive transmitting arrangement is easily assembled by simply mounting the arms 16 upon the shaft 75 and then swinging the arms to proper position against the action of the spring 80 which will insure operative engagement of the arms with the ratchet disk 11 when the parts are in proper register.

While the construction herein described and illustrated is preferred, it will be understood that changes may be made therein within the scope of the appended claims without departing from the spirit of the invention.

We claim:

1. A traveling lawn sprinkler, comprising a housing, a wheeled structure supporting said housing, a tube rotatable in and projecting from said housing, tubular sprinkler arms communicating with and projecting laterally from said tube, and drive transmission means connecting said rotatable tube and said wheeled structure, said housing including gear casing through which said tube projects and a valve casing within which said tube terminates, said casings being spaced apart to define a passage for draining water which leaks from said valve casing.

2. In a traveling lawn sprinkler, a gear casing, a valve casing, means connecting said casings in spaced relation, and a tube journaled in and extending through said gear casing, one end of said tube terminating in said valve casing, said valve casing being spaced below said gear casing to provide a passage through which water leaking from valve casing may drain.

3. In a traveling lawn sprinkler, a housing unit including a casing having an inlet chamber and a gear casing containing a lubricant, said housing unit having a drain passage between said casings, said casings having a series of aligned apertures therein, and a tubular member journaled in said apertures with one end terminating in said first casing and the other end projecting outwardly of said gear casing, said tube extending through said gear casing.

4. In a traveling lawn sprinkler, a housing unit including a valve casing and a gear casing containing a lubricant, said unit having a drain passage between said casings, means for supplying water to said valve casing, said casings hav-

ing aligned apertures, a tube journaled in said apertures with one end terminating within said valve casing and the other end projecting outwardly from the gear casing, water reactive sprinkler means mounted on the last named end of said tube, said tube extending through said gear casing, and gearing in said housing including a gear part on said tube.

5. In a traveling lawn sprinkler, a housing unit including a casing having an inlet chamber and a gear casing containing a lubricant, a tube journaled in said unit and extending through said gear housing and extending into said first casing in communication with said chamber, a shoulder on said tube engaging a wall of said gear casing to prevent endwise tube movement in liquid pressure and discharge direction, said casings being spaced apart in said unit to define a passage for draining water leaking from said first casing.

6. In a traveling sprinkler, a housing unit including a chambered portion having an inlet and an outlet, a discharge conduit journaled in said outlet, a sprinkling head carried by the outer end of said conduit and having a passage therein aligned with said conduit, a valve element in said chambered portion shiftable between open and closed positions, means for shifting said valve element to closed position, said valve element being held in closed position by water pressure, and an elongated reset rod in said tube slidable in said head passage and adapted to unseat said valve element from closed position.

7. A traveling sprinkler comprising a wheeled frame, a housing unit carried by said wheeled frame and having a chambered portion provided with an inlet and an outlet, a discharge conduit journaled in said outlet, a water reactive sprinkler head carried by the outlet end of said conduit, drive transmission means driven by rotation of said tube for propelling said wheeled frame, a normally open valve element shiftable in said chambered housing portion, and valve actuating means including a member journaled in said housing having a laterally projecting portion engageable with said valve element, and means for rotating said valve actuating means including a forwardly projecting member terminating adjacent the front end of said wheeled frame, and a reset rod extending through said conduit and slidable in and projecting from said head, the inner end of said rod bearing on said valve element.

8. A traveling sprinkler comprising a frame, an axle journaled in said frame, wheels mounted on said axle, a toothed disk fixed on said shaft, a rotatable sprinkler carried by said frame, and drive transmission means including a crank driven by said sprinkler and a pair of arms pivoted at one end to said crank and each mounting an abutment at its opposite end and engaging the teeth of said disk at substantially diametrically opposite portions of said disk, and a spring urging said arms toward each other, at least a portion of each arm being of U-shaped cross section to fit around the periphery of said disk, said abutments extending transversely of said arms.

9. A traveling sprinkler comprising a frame, an axle journaled in said frame, wheels mounted on said axle, a toothed disk fixed on said shaft, a rotatable sprinkler carried by said frame, and drive transmission means including a crank driven by said sprinkler and a pair of arms pivoted at one end to said crank and each mounting an abutment at its opposite end and engaging the teeth of said disk at substantially diametrically

opposite portions of said disk, and a spring urging said arms toward each other, each of said arms including a pair of spaced substantially parallel parts interconnected by an abutment and positioned on opposite sides of said disk.

10. A traveling sprinkler comprising a frame, an axle journaled in said frame, wheels mounted on said axle, a toothed disk fixed on said shaft, a rotatable sprinkler carried by said frame, and drive transmission means including a crank driven by said sprinkler and a pair of arms pivoted at one end to said crank and each mounting an abutment at its opposite end and engaging the teeth of said disk at substantially diametrically opposite portions of said disk, and a spring urging said arms toward each other, said arms being of channel section and positioned astraddle the marginal portion of said disk with its abutment engaging the periphery of the disk, said arms each having its central portion cut away for a portion of its length extending in the direction of

said crank from a point adjacent to said abutment.
